(57) **CLAIM**

The ornamental design for an myringotomy tube as shown and described.

DESCRIPTION

FIG. 1 is a perspective view of an myringotomy tube showing my new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The shading in FIGS. 1-7 represents a contrast in appearance only and does not represent any particular color, material, texture, or finish.

1 Claim, 2 Drawing Sheets(56)
